UNITED STATES PATENT OFFICE.

WILLIAM CROMBIE, OF LINCOLN, NEBRASKA.

TRUSS.

No. 893,146.

Specification of Letters Patent.

Patented July 14, 1908.

Application filed September 27, 1907. Serial No. 394,900.

To all whom it may concern:

Be it known that I, WILLIAM CROMBIE, citizen of the United States, residing at Lincoln, in the county of Lancaster and State of Nebraska, have invented certain new and useful Improvements in Trusses, of which the following is a specification.

This invention comprehends certain new and useful improvements in surgical appliances and relates particularly to an improved construction of a truss adapted for use in the treatment of single or double reducible inguinal rupture.

The invention has for its object a truss of this character which will be simple in construction and easy to manufacture and assemble the parts, and which will be comfortable and otherwise efficient in use, and the invention consists in certain construction and arrangement of the parts as I shall hereinafter describe.

For a full understanding of the invention reference is to be had to the following description and accompanying drawings, in which:

Figure 1 is a front elevation of the truss embodying the improvements of my invention a portion of the main supporting member being broken away as well as a portion 30 of the supporting belt. Fig. 2 is a horizontal sectional view of the truss. Fig. 3 is a detail sectional view of one of the pads. Fig. 4 is a detail view of the reinforcing and name plate hereinafter mentioned.

Corresponding and like parts are referred to in the following description and indicated in all the views of the drawings by the same reference characters.

My truss comprises a main supporting member 1 which may be of any desired shape or design and which may be constructed or formed of any sufficiently flexible material such as leather. The foundation plates 2 for the preferably pear shaped pads, are secured to the rear face of the main supporting member 1 by pivot bolts 3, which may, if desired, be in the form of screws working in the foundation plates, and the latter may, be formed of leather or any other sufficiently flexible material found suitable for the purpose. The pivot bolts 3 pass through openings 4 and 5 in the main supporting member 1, there being two sets of these openings as shown, and a plurality of openings in either one or both sets. The said openings

are also formed in a plate 6 which is preferably of metal and which is mounted on the front side of the main supporting member 1 so as to serve as a name plate as well as a reinforcing device to protect the openings 60 of the main supporting member 1 from wear. The openings 4 and 5, either or both sets, at the two ends of the main supporting member 1 may be somewhat larger than the heads of the pivot bolts 3 so that the pad at either 65 end of the main supporting member 1 may be readily detached therefrom for a purpose hereinafter set forth. The necks of the bolts 3 are preferably grooved as indicated at 7, and are adapted to slip into and engage with the contracted portions of the key hole shape slots 8 in an adjustable fastener 9 mounted on the ends of a belt 10, said belt being intended to extend around the wearer's hips. It will thus be seen that the adjustable fasteners 9 hold the pivot bolts 3 from accidental withdrawal from the openings 4 and 5. That is, as long as the fasteners are secured to the bolts, the entire device is held 70 securely in place, but whenever either one of the fasteners is removed from the bolt, the pad to which said bolt is secured may be easily detached from the main supporting member 1. It is obvious that this detachable feature may be provided for either or 85 both pads, according as judgment may dictate or the exigencies of the case require.

The two pads of the truss, designed to maintain the proper compression on the abdomen at the groin so as to press against the 90 protruding intestine or intestines, comprises in addition to the foundation plates two pouches 11 of chamois or similar soft leather or material, each of said pouches being provided at its mouth with a hem or sheath in 95 which the gathering string 12 is rove, so as to securely hold the pouch to the foundation plate in a readily removable manner. The pouches 11 may be filled with lambs' wool as indicated at 13 or any other material or substance, either medicinally prepared or otherwise.

My improved truss also embodies a suspensory which is designed to extend around the end of the scrotum and which in the present 105 instance consists of a strap 15 made of any desired width or thickness and which is preferably composed of elastic webbing. One end of the strap is inserted through an opening 16 in one of the foundation plates 2 and 110

hemmed at the end or otherwise thickened so as to prevent it from pulling out of said opening. This end, as manifest, is covered by the pouch, and the other end of the suspensory or band is detachably secured in an adjustable manner by a buckle 17 which is attached to the other pouch as shown. If desired the strap 15 may be covered by a sheath or casing 18 which may be composed 10 of any desired material which will be comfortable and sufficiently soft and smooth to prevent chafing.

Preferably the openings through which the detachable bolt is designed to pass are of key hole shape as clearly illustrated in the drawing, so that the shank of said bolt will be automatically drawn out into the contracted portion of the opening in which it is inserted, by the very position of the belt 10 itself, 20 thereby assisting in securely holding the parts in place.

It is obvious that my invention is not limited to any one size of pads or arrangement of suspensory band, as the pads may be made 25 smaller or larger as desired, and the suspensory band may be formed of either flat or round elastic webbing or be of the pouch type of suspensory.

From the foregoing description in connection 30 with the accompanying drawing it will be seen that I have provided a very simple and efficient form of truss of this character, which may be quickly applied and as readily removed and which is so constructed as to 35 permit of the attachment or its being put on or taken off without unfastening or changing the adjustment of the suspensory, inasmuch as one of the pads or both of them may be detached from the main supporting member 1 40 in the manner hereinbefore set forth.

Having thus described the invention, what is claimed as new is:

1. A truss of the character described, comprising a flexible supporting member provided at one end with an opening extending therethrough and provided at its other end with a longitudinally extending series of key hole shaped openings, a reinforcing plate extending over the front face of said flexible supporting member and formed at its ends with openings corresponding to the openings of the supporting member, pads provided with 50 bolts projecting through one of the key hole shaped openings of the flexible supporting member and the reinforcing plate and through the other openings at the opposite end of the supporting member and the plate, 55 respectively, and a supporting belt provided at one end with a fastener adapted to be slipped over the projecting end of the bolt and inserted in one of the key hole shaped slots and also provided at its opposite end with another fastener secured to the other bolt, substantially as shown and described.

2. In a truss of the character described, embodying pads and means for supporting the same, the said pads including pouches 70 and foundation plates, one of said foundation plates being formed with an opening therethrough and a buckle secured to the other foundation plate, and a suspensory held in said opening at one end and adapted 75 for adjustable engagement with the buckle at the other end.

In testimony whereof I affix my signature in presence of two witnesses.

WILLIAM CROMBIE. [L. S.]
